UNITED STATES PATENT OFFICE.

EDWARD B. JACOBSON, OF PITTSFIELD, MASSACHUSETTS, ASSIGNOR TO JACOBSON BRANDOW COMPANY, OF PITTSFIELD, MASSACHUSETTS, A CORPORATION OF MASSACHUSETTS.

ADJUSTMENT-MICROMETER FOR SPARK-COILS.

968,358.

Specification of Letters Patent. Patented Aug. 23, 1910.

Application filed November 19, 1907. Serial No. 402,803.

To all whom it may concern:

Be it known that I, EDWARD B. JACOBSON, a citizen of the United States, and a resident of Pittsfield, in the county of Berkshire and State of Massachusetts, have invented certain new and useful Improvements in Adjustment-Micrometers for Spark-Coils, of which the following is a specification.

This invention relates to induction-coil apparatus and particularly to vibrator devices commonly employed in ignition systems for internal combustion engines.

A principal object of the invention is the provision of improved means for accurately adjusting and indicating the relative positions of contact-points in apparatus of the character described. And with this and other objects in view my invention consists in certain features of construction, arrangement and combination of parts as herein-after described and claimed, reference being had to the drawings, forming a part of this specification, in which corresponding parts are designated by similar reference characters in each of the views and in which—

Figure 1 represents an exterior face view of an induction coil box, 11, of any approved construction showing a side view of a preferred form of my device operatively mounted thereon; Fig. 2, a view similar to Fig. 1, affording a rear view of my device; Figs. 3 and 4, respective top views of the parts shown in Figs. 1 and 2; the vibratile element being represented in Fig. 4 as shifted laterally from its normal operative position; Fig. 5, a longitudinal sectional view of my device drawn on the line A—A of Fig. 3; and Fig. 6, a bottom view of the free end of the supporting-arm, 22, showing the formation and engagement of the lower extremity of the core, 2, adapted to a corresponding recess provided in the said arm; Figs. 5 and 6 being detail views on an enlarged scale.

In the preferred form of my device I provide a rigid metallic supporting-arm, 22, for attachment at one end to a fixed support and having its free end extended over the vibratile element, 14, and provided with an enlarged recessed head, 24, forming a pocket containing mechanism for the proper support and adjustment of a contact-point, 25, disposed adjacent to a separate contact-point, 16, supported upon the vibratile element, 14. Said mechanism comprises a vertical stem or shaft, 26, provided with a ma-

nipulative nurl head, 1, at its upper extremity and a contact-point, 25, of platinum or other suitable conductive substance secured to its lower extremity, said shaft being removably inclosed in a bushing or hollow, movable core, 2, and engaged therewith by means of corresponding screw-threads provided on the interior surface of the core and preferably at the upper end thereof and on the shaft. Said core, 2, is designed to move vertically, up or down, within a revolving worm-gear, 18, having an extended bearing provided interiorly with a screw-thread adapted to engage with a corresponding thread on the exterior surface of the core. The core or bushing 2 is provided at its lower end with opposed flats which engage corresponding plane faces forming sides of a slot opening into the pocket in the arm 22, in which the worm wheel is seated, whereby the core when actuated vertically is prevented from rotating. Actuating the said worm-gear, 18, and in engagement therewith is a worm, 10, provided with a manipulative nurl head, 6, and constructed to revolve within a circular transverse recess in the wall of the receptacle head, 24.

Movably enveloping the extended end of the worm-gear bearing and holding the same in an upright operative position is an outer lock-casing, 27, secured between the said bearing and the wall of the receptacle head, 24, by means of a screw-thread provided exteriorly circumferentially of the casing and adapted to engage with a corresponding thread provided on the interior wall of the said head, 24. The said casing is further provided about the upper extremity thereof with a grooved flange or shoulder, 4, forming a cover for the receptacle head. Upon the top surface of the said flange are impressed or otherwise represented numerical and other characters systematically arranged to form a graduated scale. Enveloping the upper extremity of the said worm-gear bearing and frictionally secured thereon is a metallic ring, revolving with the bearing and provided with an extended lateral arm or pointer, 3, projecting freely over the impressed surface of flange, 4, in such manner as to operate as an index to the scale of the flange.

The supporting arm, 22, is secured in rigid position preferably by means of a metallic bridge, 7, placed freely athwart the

rear end of the vibratile element and secured to the insulated cover, 9, of the coil-box, 11, by means of screws, 8, passed through apertures provided in the feet of the bridge. 5 The rear end of the arm, 22, is seated in a corresponding recess provided in the top of the bridge and firmly secured in position thereon by means of bevel-headed screws adapted to engage with threaded apertures 10 provided in the bridge adjacent either side of the arm 22.

It will be apparent that my device forms part of an electric circuit and that the several parts composing the same and forming 15 a free path for the current are, where not hereinbefore specifically mentioned, constructed of metal or of some other suitable conductive substance.

The operation of my device may be described as follows:—If the contact-points 20 16 and 25 are found to be separated by an air space by which the current would be interrupted the point 25 is so adjusted by means of my device that the points will be 25 brought in slight contact sufficient to allow a free path for the passage of the current. This is done by the rotation of the nurl head, 6, upon the worm, 10, which in turn revolves the worm-gear, 18, in engagement 30 therewith. This operation causes the core, 2, supporting the shaft 26, and in engagement with the bearing of the worm-gear to rise or fall according to the rotation of the head 6. The core 2 is prevented from rotating, when actuated vertically by the worm-gear, by the formation of its lower end in engagement with the slot provided in the arm 22, as previously described. Upon the revolution of the worm-gear the pointer, 3, 40 supported thereon is rotated over the dial on the shoulder 4, indicating by reference to the scale the extent of vertical movement of the core 2, and hence the contact-point 25.

As the utility and efficiency of my device 45 and others of the same general class consists chiefly in the correct adjustment and the stationary position when in use of the upper contact-point, 25, I have specially designed the mechanism controlling this part 50 with a view to the attainment of the merits referred to. It is desirable to have means of knowing the exact position of the contact-point, 25, when properly adjusted relatively to the point on the vibratile element 55 and this advantage is attained by means of the scale and pointer. By means of my device the contact-point is adjusted with great delicacy and precision and remains in a stationary position after adjustment. And it 60 will be seen that the stem or shaft 26 may be removed from its bearing after adjustment for the inspection of the contact-point, and returned to its original position, without altering the adjustment.

65 Having fully described my invention I

claim as new and desire to secure by Letters Patent:—

1. In induction-coil apparatus, an adjustable contact-point, a movable member supporting the contact-point and adapted to be removed therewith and replaced without requiring readjustment, and means for measuring the extent of movement of the contact-point. 75

2. In induction-coil apparatus, an adjustable contact-point, a movable member supporting the contact-point, and separate means in addition to said contact-point and said supporting member for indicating the correct adjustment of the contact-point without requiring the rotation thereof. 80

3. In induction-coil apparatus, the combination in addition to said contact-point and a movable member supporting said contact-point and adapted to be removed therewith and restored to its original position without requiring readjustment of the contact-point, of means provided separately from said contact-point-supporting member for actuating the contact-point longitudinally. 85

4. In induction-coil apparatus, the combination of an adjustable contact-point, a movable member supporting said contact-point and adapted to be removed therewith and restored to original position without requiring readjustment, means for adjusting said contact-point with reference to a separate contact-point, and separate means for preventing said adjustable contact-point from being rotated. 90

5. In induction-coil apparatus, the combination of an adjustable contact-point, a movable member supporting the contact-point and adapted to be removed therewith and replaced without requiring readjustment, and means for raising or lowering said contact-point and said supporting member for adjustment without rotating the same. 105

6. In induction-coil apparatus, the combination of an adjustable contact-point, a movable member supporting the contact-point and adapted to be removed therewith and replaced without requiring readjustment, and means for indicating the correct adjustment of the contact-point. 110

7. In induction-coil apparatus, the combination of an adjustable contact-point, a movable member supporting the contact-point and adapted to be removed therewith and replaced without requiring readjustment, and means for measuring the extent of movement of the contact-point when adjusted comprising a fixed scale and a movable index for registering therewith. 115

8. In induction-coil apparatus, in combination a support, a tubular exteriorly-threaded core, a shaft projecting through the core and movably engaged therewith, said shaft being provided at one end with a contact-point and adapted to be removed there- 120

125

130

- with from the core and replaced in original position without requiring readjustment, and a worm and worm-gear coöperatively actuating said core and shaft longitudinally for the adjustment of said contact-point with reference to a separate contact-point.
9. In a make and break device, the combination with a contact-point adapted to be removed and replaced without requiring readjustment, means for the support of the contact-point, and a worm and worm-gear coöperatively actuating said contact-point supporting means, of separate means for preventing the said supporting means and contact-point from being rotated.
10. In a make and break device, the combination with a contact-point adapted to be removed and replaced without requiring readjustment, means for the support of the contact-point, and a worm and worm-gear coöperatively actuating said contact-point supporting means, of separate means for measuring the extent of movement of the contact-point.
11. In a make and break device comprising an adjustable contact-point adapted to be removed and replaced without requiring readjustment, micrometer mechanism for actuating said point toward or away from a separate adjacently disposed contact-point,

means for preventing the adjustable contact-point from being rotated, and separate means for measuring the extent of movement of the adjustable contact-point.

12. In induction-coil apparatus, the combination of a rigid support having a slotted aperture therein, a movable core carried by said support and having one end seated in said aperture whereby the core is prevented from being rotated, a stem-member projecting through the core in engagement therewith and provided at one end with a contact-point, and means for actuating the core and stem-member longitudinally for adjustment of the contact-point with reference to a separate contact-point.

13. In induction-coil apparatus, the combination with a support having a recess therein, of a contact-point, mechanism for adjusting said contact-point with reference to a separate contact-point and adapted to fit into the recess in said support, and locking means for securing said adjusting mechanism in normal operative position.

In testimony whereof I have affixed my signature, in presence of two witnesses:

EDWARD B. JACOBSON.

JAMES DIXON.

Correction in Letters Patent No. 968,358.

It is hereby certified that in Letters Patent No. 968,358, granted August 23, 1910, upon the application of Edward B. Jacobson, of Pittsfield, Massachusetts, for an improvement in "Adjustment-Micrometers for Spark-Coils," an error appears in the printed specification requiring correction as follows: Page 2, line 83, the words "means in addition to said" should be stricken out and the words and syllables *nation with an adjustable* be inserted instead; and that the said Letters Patent should be read with this correction therein that the same may conform to the record of the case in the Patent Office.

Signed and sealed this 20th day of September, A. D., 1910.

[SEAL.]

C. C. BILLINGS,

Acting Commissioner of Patents.
